UNITED STATES PATENT OFFICE.

HARRY P. FAIRCHILD, OF NEW YORK, N. Y.

DESIGN FOR A MATCH-BOX.

SPECIFICATION forming part of Design No. 20,256, dated November 4, 1890.

Application filed October 10, 1890. Serial No. 367,731. Term of patent 3½ years.

To all whom it may concern:

Be it known that I, HARRY P. FAIRCHILD, a citizen of the United States, residing at New York, in the county of New York and 5 State of New York, have invented a certain new Design for a Match-Box, of which the following is a specification.

My invention consists of a design for match-boxes of the kind or class which are carried 10 in the pocket.

The nature of my design is fully represented in the annexed cut or print, which is a face view of the same, showing one face or side of a box made in accordance with my design.

15 In outline the box is oval, and has extending around its outer edge an ornamental border composed of a series of conventionalized shells of the general style or character known as "scallops." These imitation shells are arranged end to end in a continuous line, thereby 20 imparting to the edge of the box a scalloped or wavy outline, as clearly shown in the accompanying illustration.

What I claim as my invention is—

The design for a match-box, as herein shown 25 and described.

In witness whereof I hereunto set my hand in the presence of two witnesses.

HARRY P. FAIRCHILD.
